UNITED STATES PATENT OFFICE.

HARRY SIMON, OF NEW YORK, N. Y., ASSIGNOR TO SITROUX IMPORTING COMPANY, INC., A CORPORATION OF NEW YORK.

RECEPTACLE.

Application filed June 14, 1921. Serial No. 477,419.

To all whom it may concern:

Be it known that I, HARRY SIMON, a citizen of the United States, residing at New York, in the county of New York and State 5 of New York, have invented certain new and useful Improvements in Receptacles; and I do hereby declare the following to be a full, clear, and exact description of the invention, such as will enable others skilled 10 in the art to which it appertains to make and use the same.

This invention relates to new and useful improvements in receptacles, and more particularly to a display receptacle, the main 15 object of the present invention being the provision of a receptacle or retainer for hair nets and articles of the like character whereby the quality and character of the goods can be displayed without the necessity of 20 gaining access to the interior of the receptacle.

Another object of the present invention is the provision of a receptacle comprising a single strip of material folded intermediate 25 its ends, one side portion being provided with an opening to display the contents of the receptacle and the ends of the strip being secured together by interengaging flaps.

Another object of this invention is the 30 provision of a receptacle formed of a single strip of material so folded that the exterior when folded can be used for advertising purposes and one side wall is provided with an opening to display the goods contained 35 within the receptacle and the interior of the receptacle may be used for describing the character of the goods, instructions, etc., as the receptacle itself will be formed of light weight cardboard material which will make 40 it very simple in construction and inexpensive to manufacture.

With the above and other objects in view, the invention consists in the novel features of construction, combination and arrangement of parts hereinafter more fully set forth, pointed out in the claims and shown in the accompanying drawings in which:

Figure 1 is a front elevation of my improved receptacle, illustrating the same in 50 its closed position;

Fig. 2 is a plan view of the receptacle in an open position showing the goods in place therein before the side portions of the receptacle are folded together, and

55 Fig. 3 is an end elevation.

In carrying out my invention, I provide a blank of light weight card-board or other suitable material preferably of rectangular form as shown in Fig. 2, although it will be understood that the blank may be cut in various forms and the novel feature of the invention be carried out in the same manner. The blank is folded on the line 1 at its intermediate portion so that its two ends form a back portion 2 and a front portion 3 and in order to secure the outer edges of the front and back portion together to close the receptacle, the back portion is provided adjacent each side of the blank with transverse slits 4 forming tabs 5 while the front 60 portion of the receptacle is provided adjacent each end with longitudinal slits 6 forming tabs 7. From the arrangement of the slits 4 and 6, it will be noted that when the front and back portion are brought together, the tabs will be arranged within the 65 opposing slits as illustrated in Figs. 1 and 3 to lock the front and rear portion of the receptacle in a closed position and as the tabs are resilient, the material being of a 70 suitable pliable material, the tabs can be readily disengaged from each other to gain 75 access to the interior of the receptacle.

This receptacle can be used for containing various types of articles, but in the present instance I have shown a receptacle especially adapted for the purpose of containing and displaying hair nets and in carrying out this form of the invention, the hair net is first folded into a receptacle member 8 which is formed of tissue paper or similar material and provided with an opening 9 in one wall thereof to display the contents of the receptacle and in order that the portions of the hair net which are exposed by 80 the opening 9 may be seen from the exterior of the main receptacle, a semi-circular opening 10 is formed in the front wall 3 of the main receptacle so that when the front and rear portions of the main receptacle are secured together at their outer edges, the hair net within the receptacle 8 will be displayed 85 through the opening 10 as clearly illustrated in Fig. 1.

It will be noted in the present instance 90 that the opening 10 is semi-circular in form, preferably made this shape to conform to the shape of the opening 9 in the inner wrapper or receptacle 10, but I wish it to 95 be understood that any suitable shape of 100 105 110

opening can be used in the main receptacle and also in the small receptacle which contains the goods. It will also be apparent that while I have shown an auxiliary receptacle 8 adapted to be placed within the main receptacle for containing the goods, the goods themselves may be arranged within the main receptacle and displayed through the opening 10 without the requirement of an auxiliary receptacle for the goods, it all depending upon the type and character of the goods to be displayed.

I wish it to be understood that while I have shown and described the main receptacle as formed from a rectangular blank, any desirable shape may be used as long as the goods contained within the receptacle are displayed through an opening in one side of the receptacle and the ends of the receptacle provided with opposed flap members adapted to be interengaged to retain the side flaps in their relatively closed positions as shown in Figs. 1 and 3. It will also be apparent that any desirable material may be used in the making up of the receptacle.

I claim:

1. A receptacle of the class described including a strip folded lengthwise, intermediate of its ends to form a receptacle, an auxiliary receptacle disposed between the folded portions of the main receptacle, said auxiliary receptacle having an opening to disclose the contents thereof, the main receptacle being provided with an opening upon one side whereby to display the contents of the auxiliary receptacle and interengaging means for detachably securing the ends of the strip to retain the side walls thereof in a folded position and whereby to retain the auxiliary receptacle in position within the main receptacle. 30

2. A receptacle for hair nets, comprising an inner receptacle and an outer folded receptacle, said receptacle being provided with registered openings, transverse tabs formed at one end of said outer receptacle, longitudinal tabs formed at the other end thereof for engagement for locking said receptacle in closed position. 40

In testimony whereof I affix my signature.

HARRY SIMON. 50
